UNITED STATES PATENT OFFICE.

THOMAS J. KENNEDY, OF STOCKTON, CALIFORNIA.

DRAFT-EQUALIZER FOR TUBULAR BOILERS.

1,105,798.

Specification of Letters Patent.

Patented Aug. 4, 1914.

Application filed February 26, 1913. Serial No. 750,777.

To all whom it may concern:

Be it known that I, THOMAS J. KENNEDY, a citizen of the United States, residing at Stockton, county of San Joaquin, State of California, have invented certain new and useful Improvements in Draft-Equalizers for Tubular Boilers; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in tubular boilers and particularly to a draft equalizer therefor.

In boilers now commonly in use the draft caused by the vacuum in the breeching of the boiler just below the smoke stack is such that it draws most of the draft through the upper tubes of the boiler and ordinarily the lower tubes are most entirely inactive and it is the aim of my invention to produce a means whereby this situation may be overcome and the draft equalized so as to cause all the tubes to be in operation.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

The figure in the drawing is a side elevation of a boiler showing the breeching in section to illustrate my improved structure.

Referring now more particularly to the characters of reference on the drawings, the numeral 1 designates the boiler proper which is provided with the usual tubes opening into the breeching 2. In ordinary boilers the open top 3 of the breeching near the upper end thereof causes the greatest vacuum to be at the upper end only and hence causes the operation of the upper tubes leaving the lower ones inactive. My

improved structure comprises a plate 4 secured from side to side of the breeching 2 and disposed in front of the tubes of the boiler, the upper end "b" of said member 4 being spaced a lesser distance from the ends of the boiler tubes than the lower end "a," thus causing the member 4 to be posi-

tioned in a slanting manner as shown in the drawings. This makes a greater opening at the bottom where the vacuum is ordinarily less than at the top where it is greater and these distances are proportioned according to the size of the boiler and the volume of the draft. Hence, as will be seen, the plate 4, positioned as described, will permit of a certain amount of draft passing through the upper end between said plate and the face of the boiler and a portion down below the end "a", thus causing all the tubes to be in operation. The reason for the lower end of the plate 4 being spaced a greater distance from the face of the boiler at the lower end is due to the fact that the tendency to vacuum is less under ordinary circumstances and hence, the necessity for a greater opening. The lower end "a" of the member 4 curves upwardly in an inclined manner toward the outer end of the breeching of the boiler, and hence when the products of combustion are drawn down around the lower end of the plate 4, this inclined curved end tends to shoot them directly toward the upper outer end of the breeching while those products of combustion which are drawn past the upper end of the plate 4 pass into the smokestack from the inner upper end of the breeching so that the two drafts are substantially independent and "split" whereby they will not conflict with each other in the breeching so that an equalized amount of draft may be had both from the upper and lower tubes without interference from each other.

From the foregoing description it will be readily seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention what I claim as new and useful and desire to secure by Letters Patent is:

A device of the character described comprising the combination with a tubular boiler having a breeching disposed across the end of the tubes, of a plate rigidly secured to each side of said breeching, said plate projecting over the end of said tubes, the upper end of said plate being spaced a distance

from the top of said breeching and also a distance from said tubes, the lower end of said plate being spaced a greater distance from said tubes than said upper end is disposed, and a curved portion curving outwardly from said tubes on the lower end of said plate, as described.

In testimony whereof I affix my signature in presence of two witnesses.

THOMAS J. KENNEDY.
